UNITED STATES PATENT OFFICE.

JOHN T. HAWKINS, OF TAUNTON, MASSACHUSETTS.

SHEET-DELIVERY APPARATUS.

SPECIFICATION forming part of Letters Patent No. 323,329, dated July 28, 1885.

Application filed December 1, 1884. (No model.)

To all whom it may concern:

Be it known that I, JOHN T. HAWKINS, of Taunton, in the county of Bristol and State of Massachusetts, have invented certain new and useful Improvements in Sheet-Delivery Mechanism for Printing-Machines, which invention is fully set forth and illustrated in the following specification and accompanying drawings.

10 The object of this invention is to provide a delivery apparatus more particularly applicable to that class of printing-machines designed for color-printing, whether pictorial strictly or ornamental in pattern, such color-printing demanding a delivery which will permit of the drying of the sheets in transit to the place of deposit.

15 The invention consists of the parts and combinations of parts as hereinafter described, and set forth in the claims.

20 In the accompanying drawings, Figure 1 shows in end elevation a delivery-cylinder of a printing-machine (which may or may not perform at the same time any printing function) from which the sheet is transferred to the traveling delivery mechanism shown in side elevation. Fig. 2 shows in side elevation part of the traveling delivery shown in Fig. 1, and in end view a transverse delivery provided with movable trays. Fig. 3 shows in side elevation the transverse delivery shown in Fig. 2. Fig. 4 shows in plan the transverse delivery shown in the two preceding figures.

25 In said figures the several parts are indicated by letters as follows: Upon the shaft d^3 is secured the cam g^5 , which is of proper shape to oscillate (by means of the roller g^6 , secured to the connecting-rod g^4) the strippers g' to the two positions shown in full and dotted lines, Fig. 1, at each revolution of the delivery-cylinder G . Upon the right-hand end of the shaft d^3 , Fig. 1, is secured a bevel-wheel, h . Upon a short vertical shaft, journaled in 30 projections from one of the frames A , are secured bevel-wheels h' h^2 . Upon a shaft, h^3 , journaled in frames A , is secured a bevel-wheel, h^4 , which engages the bevel-wheel h^2 . Upon the shaft h^3 are secured two or more sprocket-spiders, j , having four or more arms, each of suitable form on the ends to engage a

series of rods, j' . In a suitable stand, J , is carried a shaft, J' , carrying a second set of sprocket-spiders, J^2 , also engaging the rods j' . The rods j' are journaled in a series of 55 links, j^2 , and together with links j^3 form an endless chain. The stand J , with its sprockets J^2 , may be set at any suitable distance from the shaft h^3 , carrying sprockets j , as may be thought desirable, to enable the sheets to 60 be carried a sufficient distance to become dried before piling upon the receiving-board J^3 , attached to the stand J , the proper number of links j^2 , rods j' , &c., being made up for that purpose. Journaled in the links j^2 65 are a series of gripper-rods, j^3 , each carrying a series of grippers, j^4 , closing upon the rods j' by means of springs. Surrounding said rods, (not shown,) and on one end of each of the gripper-rods j^3 , are secured levers j^5 , each carrying a roller, j^6 . To one of the frames A is secured a stationary cam, K , and to stand J a similar cam, K' , which engage at the proper times the rollers j^6 for opening and closing successively the grippers j^4 . The speed of the 70 shaft h^3 and of its sprockets j is so proportioned by means of the bevel-wheels h , h' , h^2 , and h^4 that one arm of the sprocket j , and consequently one set of grippers j^4 , shall pass to position for grasping the issuing sheet for 75 every revolution of the delivery-cylinder G , thus traveling much slower than the sheet travels down the strippers g' at the time that the grippers j^4 seize it.

80 S S show the separate sheets, after being completely printed, as being held by grippers j^4 vertically suspended by their leading ends or heads.

85 S' shows a sheet in position as held by one set of grippers j^4 , with the strippers g' oscillated out of the way to allow its tail-end to loop and drop into the vertical position shown in full lines, Fig. 1.

90 A, Fig. 2, is a continuation of the frames A , Fig. 1, as arranged for delivering the sheets 95 individually upon trays or drying frames, the shaft J' , Fig. 2, taking the place of and performing the same function as the shaft J' , Fig. 1.

95 A² is a base-piece carrying four uprights, 100 A³, in which are journaled the shafts of the mechanism now to be described, the base-

piece A² being placed below the level of the base-piece A' sufficiently to bring the shaft d⁵, Figs. 2, 3, 4, in line with the shaft d⁶, Fig. 1, the former being a continuation of the latter. 5 Upon the shaft d⁵ is secured a spur-wheel, i, which engages an equal wheel, i', secured to a shaft, i², journaled in uprights A³. Upon the shaft i² is secured a box-cam, i³, with a groove in it, as shown in Fig. 3, engaging a roller, i⁹. 10 Fulerumed in one of the uprights is a lever, i⁴, carrying on its free end a toothed sector engaging a spur-pinion, i⁵, and at about its middle the roller i⁹, which engages the groove of cam i³. The pinion i⁵ is secured to a sleeve, i⁶, journaled in upright A³, which in turn serves as a bearing for a shaft, i⁷, at one end, the opposite end being journaled in the upright A³. Upon the sleeve i⁶ is formed a three-toothed ratchet, i⁸, and secured to shaft 15 i⁷ is a pair of sprocket-wheels, i⁹, to the one of which adjoining the toothed ratchet i⁸ is attached a pawl, i¹⁰, which engages the ratchet i⁸. The shaft i¹¹ carries a pair of sprocket-wheels, i¹², parallel to and placed at any suitable 20 distance from the shaft i⁷. Upon the sprocket-wheels i⁹ i¹² is carried an endless apron or belt, i¹³, having upon its inner side suitable projections to engage the depressions in the sprocket-wheels, and having secured upon its 25 outer surface transverse seats i¹⁴, spaced at proper distances to receive between them the trays or drying-frames for receiving the printed sheets.

The complete operation is as follows: The 30 cylinder G carries the sheet until its head reaches the points of the stripper-fingers g', embedded in circumferential grooves in said cylinder, as shown in dotted lines, Fig. 1, at which point the grippers on cylinder G (not shown) 35 release the sheet, and it passes down the stripper-fingers g' until it overtakes the open grippers j⁴, moving in the same direction at a slower rate. At this point the grippers j⁴ are closed upon the sheet by the action of the cam K, and 40 simultaneously the cam g⁵ oscillates the strippers g' into the position shown in full lines in Fig. 1, while the grippers j⁴ are at the same 45 time moving away from the strippers g', allowing the tail of the sheet to loop, as shown at S⁴, Fig. 1, and finally to be successively suspended vertically, as at SS. The endless chain 50 of grippers illustrated in Figs. 1 and 2 may be made as long as may be necessary to convey the sheets thus suspended over hot-air pipes or other drying devices, and at the end of such 55 chain of grippers the grippers j⁴ are successively opened by the cam K', allowing the sheets to drop successively in a pile either upon the receiving-board J² or upon trays on the 60 traveling apron. (Shown in Fig. 3.) When delivered to said trays, said delivery is thus accomplished: The shaft d⁵ imparts a continuous motion to the cam i³ through the gear-wheels i i', so that said cam makes one revo-

lution for each revolution of the cylinder G, 65 vibrating the sector-arm i⁴ for each sheet to be delivered. The vibration of the sector-arm i⁴ through the ratchet i⁸ rotates the sprocket-wheels i⁹ i¹², and intermittently conveys the apron i¹³ through a distance between two slats i¹⁴, the parts being so adjusted that the moving of the apron i¹³ is done while the last undelivered sheet is approaching it as suspended in a vertical position from the grippers j⁴, and it remains at rest during the time that the sheet 70 is laid and dropped upon the drying frame or tray previously laid upon said apron by an attendant, the drying frames or trays being successively supplied to the apron i¹³ at one end and removed at the other during the period of 80 said apron's rest by the proper attendants.

It is obvious that the endless apron and drying-frames may be dispensed with, if desired. It is also obvious that said apron and drying-frame apparatus may be used in conjunction 85 with any suitable delivery other than the sprocket-wheel delivery shown in Fig. 1.

Having thus fully described my said improvements as of my invention, I claim—

1. In a printing-press, in combination with 90 a grooved delivery-cylinder, a sheet-delivery consisting of a series of oscillating stripper-fingers, and two sets of sprocket-wheels carrying suitable endless chains provided with sets of grippers arranged to successively take the 95 sheets from the stripper-fingers and to convey them suspended by their upper or leading ends until, by the action of suitable stationary cams, said grippers are opened, thereby releasing the sheets in a pile upon a suitable receiving-table, substantially as set forth.

2. In a printing-machine, a sheet-delivery 100 consisting of endless chains and grippers carried upon sprocket wheels or spiders, and constructed with pivots, upon which the links 105 hinge, consisting of rods extending from chain to chain, and with gripper-shafts journaled in said links in such positions as to allow each series of grippers to close upon said rods for clamping or gripping the sheets, substantially 110 as set forth.

3. As part of the delivery apparatus of a printing or other machine, a transverse endless belt or apron intermittently operated at the proper time so as to remain at rest during 115 the deposition of a sheet upon it through suitable connection with said machine, and provided with slats rigidly secured to the outer surface of said apron at intervals apart, whereby means are provided for retaining removable drying frames or trays between said slats on top of said apron, substantially as and for the purposes set forth.

JOHN T. HAWKINS.
